CLAIM

We claim the ornamental design for the sleeve for hand held scraper, as shown and described.

DESCRIPTION

FIG. 1 is a front side perspective view of a sleeve for hand held scraper showing our new design;

FIG. 2 is a right side elevational view thereof, the opposite side being a mirror image;

FIG. 3 is a bottom elevational view thereof;

FIG. 4 is a front elevational view thereof; and,

FIG. 5 is a rear elevational view thereof;

The broken lines showing in FIGS. 1 and 3 are for illustrative purposes only and form no part of the claimed design. The broken lines showing in FIG. 3 indicate surface indicia and are intended by the inventors to be merely exemplary and nonlimitative.
